(57) **CLAIM**

The ornamental design for a spray arm for a dish treating appliance, as shown and described.

DESCRIPTION

FIG. 1 is a top, front perspective view of a spray arm for a dish treating appliance according to a first embodiment;
 FIG. 2 is a top view of the spray arm of FIG. 1;
 FIG. 3 is a right side view of the spray arm of FIG. 1;
 FIG. 4 is a left side view of the spray arm of FIG. 1;
 FIG. 5 is a front view of the spray arm of FIG. 1;
 FIG. 6 is a rear view of the spray arm of FIG. 1;
 FIG. 7 is a top, front perspective view of a spray arm for a dish treating appliance according to a second embodiment;
 FIG. 8 is a top view of the spray arm of FIG. 7;
 FIG. 9 is a right side view of the spray arm of FIG. 7;
 FIG. 10 is a left side view of the spray arm of FIG. 7;
 FIG. 11 is a front view of the spray arm of FIG. 7; and,
 FIG. 12 is a rear view of the spray arm of FIG. 7.
 Portions of the drawings shown in broken lines form no part of the claimed design.
